UNITED STATES PATENT OFFICE.

ALBERT TROUP COX, OF ATLANTA, GEORGIA.

COLLAR IRONING AND SHAPING MACHINE.

No. 861,240.

Specification of Letters Patent.

Patented July 23, 1907.

Application filed November 28, 1905. Serial No. 289,444.

To all whom it may concern:

Be it known that I, ALBERT TROUP COX, a citizen of the United States, residing at Atlanta, in the county of Fulton and State of Georgia, have invented certain new and useful Improvements in Collar Ironing and Shaping Machines, of which the following is a specification.

My present invention pertains to improvements in collar-ironing and shaping machines, the construction 10 and advantages of which will be hereinafter set forth.

The object of the invention is to provide a simple and effective machine, which will rapidly handle the collars and at the same time impart the proper shape thereto, giving likewise a high finish or burnished 15 effect to the outer face of the folded section of the collar.

The machine is illustrated in the annexed drawings, wherein:

Figure 1 is a sectional elevation thereof; Fig. 2 a 20 transverse vertical sectional view, on the line 2--2 of Fig. 1; Fig. 3 a similar view, on the line 3--3 of Fig. 1; Fig. 4 a top plan view of the guide and the grooved ironing roll; Fig. 5 a perspective view of the guide, the same being partly broken away to more clearly 25 illustrate its form and construction; and Fig. 6 a vertical sectional view, on the line 6--6 of Fig. 1.

The machine in its breadth may be said to comprise a grooved roll, a rotary disk, the edge of which extends into the groove in the roll, a positively-driven feed 30 wheel coöperating with the disk and acting on the band of the collar to feed the same, and means for positively rotating the grooved roll in opposition to the direction of rotation of the feed wheel and the disk and at a speed materially higher than that of the other 35 parts.

In the drawings, A designates the base of the machine, to one end of which is secured a standard or support B, of the form best shown in Fig. 3. The upper portion of said standard is enlarged and bored out to 40 form a bearing or support for a horizontally-disposed shaft C, said shaft carrying at its extreme outer end a roll D, provided with a groove E which extends around the periphery thereof adjacent to its outer end. Said groove, as will be seen upon reference to Figs. 1 and 4, 45 is substantially V-shaped in contour. The roll D is made hollow or cored out, and is adapted to be heated by a flame passing from a burner F, Fig. 2.

Secured to the shaft C is a driving-wheel G, and also 50 a bevel-gear H, the latter meshing with a similar gear I mounted upon the upper end of a shaft J, which is carried by the standard B, as shown in Fig. 3. Shaft J likewise has secured to it a pinion K which imparts motion to a large gear L, through the intermediate gears M and N which, as will be seen upon reference to 55 Fig. 1, are carried by two vertically-disposed shafts O and P, secured in the base of the ma-

chine. Gear L is mounted upon the lower end of a vertically-disposed shaft or spindle Q, passing through a sleeve or bushing R, carried in the outer end of an arm or bracket S, extending outwardly from a post or 60 standard T, which, as will be seen upon reference to Figs. 1 and 6, is secured to the base at the end opposite that upon which the standard B is mounted.

To the upper end of shaft Q is secured a friction driving wheel U, the latter being preferably formed of a 65 disk of rubber of the proper thickness secured between a pair of washers, as clearly shown in Fig. 1.

Pivottally mounted upon the upper end of the post or standard T is a frame or casting V, which is provided with a sleeve or bearing bushing W, forming the support for a shaft X. Secured to the upper end of said shaft is a conical disk Y, the lowermost edge of the disk passing into the groove E in the roll D, as will be seen upon reference to Figs. 1 and 2. The portion of the disk that stands immediately above the roll assumes a substantially vertical position, and the feed wheel U makes contact with the inner face thereof, or is arranged to come into such close proximity to said inner face as to grasp the band of a collar which may be passed through the machine. The shaft X is held 70 in position in the bearing sleeve by a collar Z, secured upon the lower end of said shaft.

Extending downwardly from the frame or casting V is an arm A' (Figs. 1 and 6), the lower end of said arm being provided with an opening B' and with a socket 85 or recess C'. A rod D', which passes freely through said opening B', is secured at its opposite end to a lug E' extending outwardly from the bracket S, said lug being likewise provided with a socket or recess F'. A spring G' encircles the rod, the ends of the spring being seated 90 in the sockets C' and F'. A nut H' is mounted upon the outer end of the rod and bears against the outer face of the depending arm or lever A'. The spring serves normally to throw said arm or lever outward and thereby bring the lower edge of the disk Y down 95 into the groove in the roll. By regulating the nut H' the space left between the lower edge of the disk and the bottom of the groove may be changed as described. Furthermore, the spring will hold the disk down upon the work with a yielding pressure and allow the disk 100 to rise, should any hard substance be passed between the disk and the roll. The spring likewise holds the disk against the periphery of the feed roll with a yielding pressure.

To enable collars to be readily fed into the machine, 105 I employ a feed-way or guide of the form best shown in Figs. 4 and 5, said guide comprising a trough-shaped member Y', provided with outwardly-flaring wings J', said wings converging and passing into the vertically-disposed members of the trough which stand adjacent 110 to and slightly overlap the disk Y. The guide is supported by a standard K', secured to the base to one

side of the feed wheel and roll. This guide will be mounted upon one for the other side of the machine according to the direction of rotation of the parts.

While the guide is not absolutely necessary to the 5 operation of the mechanism, it facilitates the entrance of the collars between the operative parts thereof, and consequently increases the output of the machine.

In order to inclose the gears H, L, M and N, I employ a guard, preferably composed of a single piece of 10 metal bent to form, and having an arch-shaped section L' from which extend vertically-disposed members M', said members extending outside of the gears L, M, and N, on each side of the machine, as will be seen upon reference to Fig. 2. The lower edges of said members 15 M' are turned outward and secured to the base by suitable screws. By this simple arrangement the gears are practically inclosed, so that there is no danger of anything being caught thereby.

As above noted, and as will be seen upon reference 20 to Fig. 1 of the drawings, the gearing is such as to impart a relatively rapid rotation to the burnishing or ironing roll D in one direction, while the feed wheel U is rotated in the opposite direction and at a slower speed. Inasmuch as the rotation of the disk Y is dependent 25 upon the rotation of the wheel U, said disk will also rotate at a speed materially slower than that of the burnishing or ironing roll D. Consequently, the edge of the collar which is forced down into the groove E by the disk Y will be burnished by the roll, and not 30 simply pressed.

It has been found from actual use of the machine that collars finished thereon take the desired shape or contour, or in other words, are given the proper set to enable them to be worn with comfort. Stated in a different 35 way, the collars do not come out of the machine in an exactly circular form, but the forward edges thereof are given a slight dip or may be said to droop, thus giving to the collars the necessary or desired shape.

It will, of course, be understood that the collars, before 40 being passed through this machine, have been ironed flat, and that before they are fed to the machine the seam or line of fold is dampened, in order that the collar may be bent without breaking the fiber of the linen.

45 As will be seen the collar is fed through the machine by the collar-band, which is clamped between the feed wheel U and the inner face of the disk Y, and by this arrangement I am enabled to rotate the ironing roll in a direction opposite to that of the feed of the collar.

50 Having thus described my invention, what I claim is:

1. In a machine of the character specified, the combination of an ironing roll; a feed wheel; a disk coöperating with said roll and wheel; and means for driving said roll and wheel in opposite directions, whereby the adjacent coöperative portions of the disk and roll will likewise move or travel in opposite directions.

2. In a machine of the character specified, the combination of a grooved ironing roll; a disk having its edge extending into the groove of said roll; a feed wheel coöperating with one face of the disk and arranged to clamp a collar between its edge and the disk; and means for rotating said roll and wheel at different speeds, the coöperative peripheries of the disk and roll traveling in opposite directions.

3. In a machine of the character specified, the combination of a grooved ironing roll; a rotatable disk having its edge extending into the groove of said roll; means for nor-

mally holding said disk in its adjusted position; a feed wheel coöperating with said disk to grasp a collar and feed the same through the machine; and means for imparting rotary movement to said disk and roll so as to produce travel in different directions at their adjacent or coöperative peripheries.

4. In a machine of the character specified, the combination of a grooved ironing roll; means for rotating the same at a relatively high speed; a rotatable disk arranged above the roll and having its edge extending into the groove therein; means for yieldingly pressing said disk downwardly toward the bottom of the groove; a feed wheel arranged to one side of the disk and adapted to impart motion thereto; and means for positively driving said wheel at a rate of speed less than that of the speed of the ironing roll.

5. In a machine of the character specified, the combination of a grooved ironing roll; a conical disk having its edge entering the groove in said roll and being free to rotate independently of the roll; a feed wheel arranged to coact with the inner face of the disk to feed a collar over the edge of the disk and through the groove in the roll; and means for rotating said roll and wheel in such directions as to cause the adjacent coöperative portions of the roll and disk to move past each other in opposite directions.

6. In a machine of the character specified, the combination of a grooved ironing roll; a conical disk having its edge entering the groove in said roll and being free to rotate independently of the roll; a feed wheel arranged to coact with the inner face of the disk to feed a collar over the edge of the disk and through the groove in the roll; means for rotating said roll at a relatively high rate of speed; and means for rotating the wheel at a slower speed and in a direction the same as that of the travel of the collar through the machine.

7. In a machine of the character specified, the combination of a suitable base; a driving shaft mounted thereon; a grooved ironing roll carried by said shaft; a pivoted frame mounted upon the base; a freely-revolvile disk carried by said pivoted frame; means for normally holding the edge of said disk in the groove of the ironing roll; a feed wheel coacting with one face of the disk to grasp a collar and feed the same through the machine; and gearing interposed between the driving shaft and wheel for imparting rotation to said wheel in a direction reverse to that of the roll and at a slower speed than the roll, whereby motion in opposite directions and at different speeds will be imparted to the adjacent coöperative portions of the roll and disk, substantially as and for the purpose described.

8. In a machine of the character specified, the combination of a base; a driving shaft mounted in a suitable support carried by the base; a grooved ironing roll secured upon one end of the shaft; a frame or casting pivotally mounted upon the opposite end of the base; a conical disk carried by the frame and freely revolvile independently of the roll; an arm or lever extending downwardly from the frame or casting; a spring acting upon said arm and serving to throw the lower edge of the disk downwardly into the groove of the ironing roll; means for imparting motion to the driving shaft; a feed wheel coacting with one face of the disk; and gearing interposed between said wheel and the shaft, for rotating the wheel in a direction reverse to that of the rotation of the roll and at a slower speed than the roll, whereby the adjacent coöperative peripheral portions of the roll and disk will travel in opposite directions and at different speeds.

9. In a machine of the character specified, the combination of a grooved ironing roll; a disk arranged above said roll and freely rotatable independently thereof; a feed wheel coacting with said disk; means for rotating said roll and wheel so as to impart to the coacting portions of the disk and roll motion in opposite directions; and a guide arranged in line with the lower edge of the disk and the groove in the roll, said guide serving to facilitate the introduction of collars into the machine.

10. In a machine of the character specified, the combination of a grooved ironing roll; a disk coöperating therewith; means for causing the adjacent coöperative portions

of said roll and disk to move past each other in opposite directions; a feeding wheel working in conjunction with the disk and serving to feed a collar through the machine; and means for normally and yieldingly holding said disk 5 toward the face of the wheel.

11. In a machine of the character specified, the combination of a grooved ironing roll; a disk coöperating therewith and adapted to enter between the folds of a collar; a feeding wheel provided with a yielding face, said wheel working in conjunction with the disk and serving to feed the collar through the machine; and means for normally holding said disk toward the face of the wheel with a yielding pressure.

12. In a machine of the character specified, the combination of a grooved ironing roll; a rotatable disk having its edge extending into the groove of said roll and adapted to pass between the folds of a collar; and a positively-driven wheel coacting with said disk and serving to clamp the band of the collar and feed the same through the machine.

13. In a machine of the character specified, the combination of a grooved ironing roll; a rotatable disk having its edge extending into the groove of said roll; a positively-driven feed wheel coacting with one face of the disk; and means for yieldingly pressing the disk toward the face of the feed wheel.

14. In a machine of the character specified, the combination of a grooved ironing roll; a rotatable disk having its edge extending into the groove of said roll; a positively-driven feed wheel coacting with one face of the disk; and means for yieldingly pressing the disk toward the face of the feed wheel and into the groove in the ironing roll.

In testimony whereof I have signed my name to this specification in the presence of two subscribing witnesses.

ALBERT TROUP COX.
